CLAIM

The ornamental design for a finger sleeve, as shown and described.

DESCRIPTION

The present application incorporates U.S. Design application Ser. No. 29/928,353, filed Feb. 9, 2024, herein by reference in its entirety.

FIG. 1 is a perspective view of a finger sleeve showing my new, original and ornamental design;

FIG. 2 is a top view thereof;

FIG. 3 is a bottom view thereof;

FIG. 4 is a right-side view thereof;

FIG. 5 is a left-side view thereof;

FIG. 6 is a back view thereof;

FIG. 7 is a front view thereof;

FIG. 8 is a perspective view thereof showing an example massage device inserted in the finger sleeve; and,

FIG. 9 is a perspective view thereof showing an example massage device and an example finger inserted in the finger sleeve.

The broken lines shown in the figures are for the purposes of illustrating portions of the finger sleeve, which form no part of the claimed design. The human hand shown in broken lines in FIG. 9, and the massage device shown in broken lines in FIGS. 8 and 9, are for the purposes of illustrating environmental structure, which form no part of the claimed design.
